TONE CONTROL ARRANGEMENT WITH
INDICATORS

Rudolph G. Miller, Rochester, and Garrard Mountjoy, Canandaigua, N. Y., assignors to Stromberg-Carlson Company, a corporation of New York

Application June 8, 1949, Serial No. 97,771

10 Claims. (Cl. 177—311)

1

Our invention relates to improvements in tone control devices used in the electrical reproduction of sound, and more particularly to mechanical arrangements for controlling the frequency response of amplifiers and the like.

Our invention finds greatest application in amplifiers for reproducing music and other entertaining and informative sounds of the type commonly encountered in radio programs and phonograph records. The amplifiers used for this purpose usually employ electron tubes to provide the required amplification. However, the high- and low-frequency response characteristics of these amplifiers may be either excessive or insufficient for a particular program. For example, too much emphasis on the bass notes may result in a "boomy" quality of voice reproduction, although it may be desirable for certain kinds of music. On the other hand, the presence of noise in the program material may make it desirable on some occasions to diminish the high, or treble, response of the amplifier. Similarly, it may be desirable to "boost" the high or low frequencies, depending upon the characteristics of the program material.

It is known to provide bass and treble tone controls for selecting the low-and high-frequency responses of the amplifier independently of each other. These controls are usually potentiometers. Prior to our invention, it was necessary to "read" or estimate the individual settings of these potentiometers, in order to visualize the overall type of response resulting. As is well known, the balance between bass and treble is fully as important as the ability to augment or diminish the bass or treble responses individually. Thus, if it is desired for any reason to mute the high frequency response, it may be advisable to diminish the low frequency response also. This balance is generally termed "tonal balance."

It is therefore an object of our invention to provide means for quickly and easily determining the particular frequency response being obtained in an amplifier.

It is also an object of our invention to provide an indicator of the tonal balance of an amplifier which enables tonal balance adjustments to be easily visualized.

It is a further object of our invention to provide an indication of the tonal balance of an amplifier by means of colored light.

It is still a further object of our invention to provide a tonal balance indicator for an amplifier in which various distinctive colors, each having

2

a depth of coloration proportional to the emphasis being placed on a particular portion of the response characteristic of the amplifier, are mixed to provide an additional color indicative of the tonal balance selected.

These and other objects of our invention we accomplish by associating distinctive reference indicia with the bass and treble tone controls, respectively. We arrange these indicia to be seen by the operator of this tone control assembly in such a way that he interprets not only the settings of the individual controls by means of the respective indicia, but can also interpret the degree of tonal balance being used by a superposition of these indicia.

In general, we prefer to provide an arrangement in which these indicia comprise lights of distinctive colors. In a preferred embodiment of our invention, explained in detail later in this specification, we provide a source of light inside a translucent cylinder. This cylinder is coupled for rotation to one of the tone controlling means. A second cylinder is disposed coaxially around the first cylinder, and is coupled to the other tone controlling means. Each cylinder is distinctively colored with a density of coloration which varies with the degree of actuation of the respective tone controlling means. The cylinders are so disposed with respect to each other that part of the colored light distinctive to each of the cylinders is seen by the operator of our invention. The remaining part of the light of one cylinder is arranged to overlap the remaining part of the light of the other cylinder. In this way, distinctive coloration is produced in the overlapped area which is interpreted by the operator as indicative of the degree of tonal balance in use. The colored areas appear to the operator of our invention as shown in Figure 2 of the accompanying drawing.

The foregoing and other objects and advantages of our invention will become apparent as the following description proceeds, and the features of novelty which characterize our invention will be pointed out with particularity in the claims annexed to and forming a part of this specification.

For a better understanding of our invention, reference may be had to the accompanying drawing in which Fig. 1 represents a partial section along line A—A of Fig. 2, of a preferred embodiment of our invention, as viewed from the top, and Fig. 2 is a front view of our invention, as seen by the user of an amplifier to which it is connected.

Referring now to Fig. 1, which illustrates the preferred form of our invention, we provide a bass tone control potentiometer 1, the shaft of which is parallel to the front panel 2. We also provide a treble tone control potentiometer 3 similarly arranged. Potentiometers 1 and 3 are supported by means of brackets 4 and 5, respectively, which are fastened to frame 6 by means of screws 7. Wires 8 from these potentiometers may be gathered into a cable 9 leading to the chassis 33 of the amplifier. It should be understood that our invention is equally applicable to an amplifier built on an individual chassis or to an amplifier constructed on a chassis common to the other circuits, such as a radio receiver. A thumb wheel 10, which may be knurled on its outer circumference 11, is secured to the shaft of bass tone control potentiometer 1 by suitable fastening means, such as set screw 12. A thumb wheel 13, which may also be knurled on its outer circumference 14, is suitably secured to the shaft of treble tone control potentiometer 3 as by means of set screw 15. Supported by thumb wheel 13 is a lamp socket 16 insulated from thumb wheel 13 by means of insulator 18. The center contact 17 of socket 16 is secured to thumb wheel 13. The outer portion of the socket is supplied with electric current by wire 19 which passes through hole 20 in thumb wheel 14, passes around the shaft of treble tone control potentiometer 3 and is secured to a terminal block 21. Terminal block 21 may be supplied with current by wire 22, which may be included in cable 9 to the amplifier chassis. Secured by socket 16 is a lamp 23 which is lighted whenever the amplifier is turned on.

A translucent cylinder 24 is secured to thumb wheel 13 by means of screw 25. Screw 25 projects through thumb wheel 13 in order to provide a stopping action when it strikes stop 26. (Stop 26 is indicated schematically, since its size and location depend on the amount of rotation required for potentiometer 3. In some cases, a stop is provided within the case of the potentiometer.) A second translucent cylinder 27 is secured to thumb wheel 10 by means of screw 28. Screw 28 projects through thumb wheel 10 in order to provide a stopping action when it strikes stop 29. (Stop 29 is shown schematically for the same reason as stop 26 is.) It will be noted that the bass and treble tone control potentiometers are so arranged that translucent cylinder 27 is disposed within the translucent cylinder 24.

Secured to at least a portion of one of the surfaces, preferably the inner circumference, of translucent cylinder 24 is a strip or coating of distinctively colored translucent material 30. We prefer that the portion of the surface covered by strip 30 comprise about two-thirds of the axial length of cylinder 24. The density of coloration of strip 30 is graduated smoothly in a circumferential direction, but is uniform in the axial direction. The minimum density of strip 30 is arranged to be nearest the operator at 31 (located in front of panel 2) when the treble tone control 3 is in the position to produce the maximum treble response. We prefer that strip 30 be colored blue, although any color may be used without departing from the spirit of our invention. The best effect is produced if the color is of the group known as "cool," because human beings tend to associate high notes with cool colors and low notes with "warm" colors.

A translucent strip or coating 32 is secured to at least a portion of one of the surfaces of the axial length, preferably the inner circumference,

of cylinder 27. We prefer that the portion of the surface covered by strip 32 comprise about two-thirds of the axial length of cylinder 27, such that one third of strip 32 overlaps one third of strip 30 in cylinder 24. Strip 32 is distinctively colored, i. e., strip 32 has a color different from that of strip 30. Again, any color (other than that used for strip 30) may be used without departing from the spirit of our invention, but we prefer to use a warm color. We find that the best effect is obtained if the color selected for strip 32 is red. The density of coloration of strip 32 varies smoothly in a circumferential direction from minimum to maximum but is preferably uniform in the axial direction. The minimum density is arranged to be nearest the operator at 31 when the bass tone control potentiometer is in a position to produce minimum bass response. We wish to point out here that the use of separate translucent strips 30 and 32 is not necessary if corresponding axial lengths of the translucent cylinders 24 and 27 are each distinctively colored, while the remaining portion of the axial length remains translucent and uncolored. If it is not desired to give separate color indication of the positions of the bass and treble control potentiometers, the entire axial length of cylinders 24 and 27 may be colored.

The effect of the described embodiment of our invention upon the operator at 31 is represented in Fig. 2. Thumb wheels 10 and 13 project through the front panel 2 and may be easily rotated by reason of the knurling of the outer circumferences 11 and 14 respectively. The outer surface of the outer cylinder 24 is nearest the operator. The operator sees three areas of colored light, the left-hand one being red, the center one purple, and the right-hand one blue. The shade of red seen in the left-hand area will depend upon the setting of the bass tone control potentiometer, and will be lightest if the bass response is at a minimum. The blue area will be most lightly colored if the treble tone control potentiometer is set to produce maximum treble response. The colors of the center section will be proportional to the densities of the red and blue portions which are combined to form purple. In this way, the particular shade of purple produced in the center area uniquely corresponds to a particular combination of settings of the bass and treble tone control potentiometers. If desired, the embodiment just described may be fastened to the front panel of the cabinet in which the amplifier is housed. The front of the amplifier chassis 33 may then be placed in contact with spring 34. A ground return for the current supply of the lamp 23 is therefore conveniently provided. When this arrangement is used, it is not necessary to remove the tone control assembly from the front panel when it is desired to service the amplifier chassis alone.

We particularly wish to point out the means by which the lamp 23 is continuously provided with current during and after rotation of thumb wheel 13. One or more turns of wire 19 are wound around the shaft of treble tone control potentiometer 3 such that the turn (or turns) is nearly tight on the shaft when the shaft is in its position of minimum rotation, and may be completely unwound in the position of maximum travel.

While we have shown and described a specific embodiment of our invention, other modifications will readily occur to those skilled in the art. For example, other translucent means may be substituted for cylinders 24 and 27. In one modifi-

cation, means other than color may be employed, as numerals, for example. Another arrangement is to omit the overlapping disposition of color and the attendant "blended" band or area. We do not, therefore, desire our invention to be limited to the specific arrangement shown and described, and we intend in the appended claims to cover all modifications within the spirit and scope of our invention.

What we claim is:

1. In a tone control assembly for amplifiers and the like; bass tone controlling means; treble tone controlling means; first translucent means associated with said bass tone controlling means; second translucent means associated with said treble tone controlling means; each of said translucent means bearing distinctive reference indicia; means for projecting light through both translucent means; and means for varying the relative positions of said translucent and said light means for changing the illuminated impression conveyed to the operator of said tone controlling means in accordance with the relative settings of said tone controlling means.

2. In a tone control assembly for amplifiers and the like; bass tone controlling means; treble tone controlling means; first translucent means associated with said bass tone controlling means; second translucent means associated with said treble tone controlling means; each of said translucent means bearing distinctive reference indicia; said reference indicia being respectively arranged to at least partially overlap; means for projecting light through both translucent means; and means for varying the relative positions of said translucent and said light means for changing the illuminated impression conveyed to the operator of said tone controlling means in accordance with the relative settings of said tone controlling means.

3. In a tone control assembly for amplifiers and the like; bass tone controlling means; treble tone controlling means; first translucent means associated with said bass tone controlling means; second translucent means associated with said treble tone controlling means; each of said translucent means being distinctively colored, the character of the coloring of each means differing across the surface thereof; means for projecting light through both translucent means; and means for varying the relative positions of said translucent and said light means for varying the color impression conveyed to one operating said tone controlling means in accordance with the various settings of said tone controlling means.

4. In an amplifier, the combination of bass tone controlling means, treble tone controlling means, first translucent means disposed for movement by actuation of said treble tone controlling means, second translucent means disposed for movement by actuation of said treble tone controlling means, each of said translucent means being distinctively colored, the density of the coloration varying across the surfaces of said translucent means, and a source of light arranged to shine through different portions of said translucent means in tandem, as said means are moved, whereby the color of the light emerging from said second translucent means indicates the degree of tonal balance selected with said tone controlling means.

5. In an amplifier, the combination of bass tone controlling means, treble tone controlling means, a first translucent means coupled for rotation to said bass tone controlling means, a second translucent means coupled for rotation to said treble

tone controlling means, each of said translucent means being distinctively colored and mounted for overlapping relationship, the density of coloration varying smoothly with the amount of rotation of the respective one of said tone controlling means, and a source of light arranged to shine through the overlapping portions of said translucent means, whereby the color of the light emerging from the said second translucent means indicates the particular tonal balance selected with said tone controlling means.

6. In an arrangement for selecting at will the tonal balance of an amplifier, the combination of a first translucent cylinder coaxially disposed within a second translucent cylinder; means for manually rotating said cylinders independently of each other; a source of light disposed within the inner one of said cylinders; bass tone controlling means coupled for rotation to one of said cylinders; treble tone controlling means coupled for rotation to the other of said cylinders; each of said cylinders having distinctive coloring means such that the density of coloration changes, with rotation, whereby the color of the light emerging from the outer one of said cylinders indicates the degree of tonal balance selected with said tone controlling means.

7. In an arrangement for selecting at will the tonal balance of an amplifier, the combination of a first translucent cylinder coaxially disposed within a second translucent cylinder; means for manually rotating said cylinders independently of each other; a source of light disposed within the inner one of said cylinders; bass tone controlling means coupled for rotation to one of said cylinders; treble tone controlling means coupled for rotation to the other of said cylinders; each of said cylinders having distinctive coloring means such that the density of coloration changes, in a circumferential but not an axial direction, with rotation, whereby the color of the light emerging from the outer one of said cylinders indicates the degree of tonal balance selected with said tone controlling means.

8. In an arrangement for selecting at will the tonal balance of an amplifier, the combination of a first translucent cylinder coaxially disposed within a second translucent cylinder; means for manually rotating said cylinders independently of each other; a source of light disposed within the inner one of said cylinders; bass tone controlling means coupled for rotation to one of said cylinders; treble tone controlling means coupled for rotation to the other of said cylinders; each of said cylinders having distinctive coloring means such that the density of coloration changes with rotation, said coloring means at least partially overlapping, whereby three colored areas are seen by the operator of said tone controlling means, the color of the first of said areas being indicative of the setting of said bass tone controlling means, the second of said areas being indicative of the setting of said treble tone controlling means, and the third of said areas having a color resulting from the overlapping of said coloring means, thereby indicating the degree of tonal balance selected.

9. In an arrangement for selecting at will the tonal balance of an amplifier, the combination of a first translucent cylinder coaxially disposed within a second translucent cylinder; means for manually rotating said cylinders independently of each other; an electric source of light disposed within and supported by said first translucent cylinder, means for supplying electricity continu-

ously to said source during and after rotation of said first translucent means; bass tone controlling means coupled for rotation to the other of said cylinders; treble tone controlling means coupled for rotation to the other of said cylinders; each of said cylinders having distinctive coloring means such that the density of coloration changes, in a circumferential but not an axial direction, with rotation, whereby the color of the light emerging from the outer one of said cylinders is formed by passage through each of said distinctive coloring means, and therefore uniquely indicates the degree of tonal balance selected with said tone controlling means.

10. In an arrangement for selecting at will the tonal balance of an amplifier, the combination of a frame; first and second tone control potentiometers for controlling different ranges of the responses of said amplifier; said potentiometers mounted on said frame with their shafts extending toward each other; first and second thumb wheels secured to said first and second shafts respectively; first and second translucent cylinders operatively associated with said first and second thumb wheels respectively, the first of said cylinders being coaxially disposed within said second cylinder; said potentiometers, thumb wheels and cylinders all having their axes coincident and parallel to the front of said chassis; an electrical source of light secured within the first said cylinder; means for continuously supplying electricity to said source during rotation of said first cyl-
